(57) **CLAIM**

The ornamental design for a cable organizer, as shown and described.

DESCRIPTION

FIG. 1 is a top-front-right perspective view of a cable organizer in accordance with the design;

FIG. 2 is a bottom-front-left perspective view thereof;

FIG. 3 is a front side view thereof;

FIG. 4 is a back side view thereof;

FIG. 5 is a left side view thereof, the right side view being identical;

FIG. 6 is a top plan view thereof;

FIG. 7 is a bottom plan view thereof; and,

FIG. 8 is a cross-sectional view thereof, taken along line 8-8 of FIG. 1.

1 Claim, 6 Drawing Sheets(56)
